(57) **CLAIM**

The ornamental design for a securement member of electrical connector, as shown and described.

DESCRIPTION

FIG. 1 is a top, left, front perspective view of a securement member of electrical connector according to one embodiment of our design, the securement member configured to secure the electrical connector to an underlying substrate; FIG. 2 is a bottom, right, rear perspective view of thereof; FIG. 3 is a bottom, left, front perspective view of thereof; FIG. 4 is a top, left, rear perspective view of thereof; FIG. 5 is a right side elevation view thereof; FIG. 6 is a left side elevation view thereof; FIG. 7 is a top plan view thereof; FIG. 8 is a bottom plan view thereof; FIG. 9 is a rear elevation view thereof; FIG. 10 is a front elevation view thereof; FIG. 11 is a top, right, front perspective view of a securement member of electrical connector according to one embodiment of our design, the securement member configured to secure the electrical connector to an underlying substrate;

FIG. 12 is a bottom, left, rear perspective view of thereof; FIG. 13 is a bottom, right, front perspective view of thereof; FIG. 14 is a top, right, rear perspective view of thereof; FIG. 15 is a left side elevation view thereof; FIG. 16 is a right side elevation view thereof; FIG. 17 is a top plan view thereof; FIG. 18 is a bottom plan view thereof; FIG. 19 is a rear elevation view thereof; and, FIG. 20 is a front elevation view thereof.

In a preferred embodiment, the nature of this product is a securement member of electrical connector for securing the electrical connector to an underlying substrate.
